Atty

UNITED STATES PATENT OFFICE.

WILLIAM M. SCHOLL, OF CHICAGO, ILLINOIS.

METATARSAL-ARCH-SUPPORTING PAD OR CUSHION.

Application filed December 1, 1924. Serial No. 753,328.

One of the objects of the invention is to provide improved means to be placed in a shoe and located under the foot of the wearer, serving as an insole of the shoe 5 and acting as means for preventing movement of an arch support attached thereto and carried thereby.

Another object of the invention is to provide a flexible insole, such for example as 10 leather, for carrying the pads or cushions to raise and support a defective metatarsal arch, and flexible means for preventing the insole from wrinkling or creeping.

Another object is the provision of an im- 15 proved means for holding and retaining an arch support properly in a shoe.

Other objects, advantages and benefits of the invention will readily appear to persons skilled in the art from a consideration of the 20 following description when taken in conjunction with the drawings, wherein:

Figure 1 is a bottom plan view of the device showing the cover turned back and showing a strip of thin steel embedded in 25 the sole part, to prevent it from being formed into short undulations, crimps or wrinkles.

Figure 2 is a longitudinal central section taken on line 2—2 of Figure 1 showing the 30 device right side up.

Figure 3 is a section taken on line 3—3 of Figure 1, as when the latter is in place in a shoe.

Figure 4 is a transverse section taken on 35 line 4—4 of Figure 1.

In all of the views, the same reference characters are employed to indicate similar parts.

5 is an insole made to fit inside the shoe 40 and composed preferably of leather. It is laterally expanded at its front end and is skived across the front edge at 6 to make the end tapered to prevent an abrupt shoulder within the shoe. The front end of the insole 45 5 is cupped at 7 within which cup is received a pad or cushion 8. The pad or cushion 8 is ovate in outline and tapers upwardly and forms the means for supporting the metatarsal arch of the foot. The 50 pad 8 may preferably be made of felt or soft rubber, or the like, and after it has been secured to the front end of the insole, the bot-

tom of the insole is covered by a covering 9 which may be of leather, chamois, buck skin, or the like.

When an insole, such as described, is placed in the shoe, and especially when the front end of it is elevated, there is a tendency for it to form into creases or to wrinkle thereby producing a disagreeable effect upon 60 the foot.

To prevent this, I preferably split the edge of the insole from end to end on one side, as at 10, and separate the split parts and then insert a relatively thin steel strip 65 11. After the thin steel strip 11 has been inserted between the split parts of the insole, the parts are glued together as shown at 12 in Figure 4. When the strip of steel is in place, the insole 5 cannot wrinkle or become 70 corrugated because of the resiliency of the steel strip which tends always to straighten the insole, and when the insole is cut to fit the shoe, the arch support 8 will remain constantly in the position in which it has been 75 placed for the purposes mentioned.

The bottom surface of the insole carrying the cushion 9 is overlaid with a cover 13 which may be stitched around the edge through the insole and cover, as at 14. The 80 cover is shown turned back in Figure 1 in order to expose the underlying parts.

The arch supporting pad 8 is parti-oval in cross section on line 3—3 as shown in Figure 3, and from this line rearwardly the pad 85 tapers less abruptly, as shown in Figure 2. The pad 8 is shown as a support for the first, second and third metatarsals of the right foot. It may be shifted in position, however, to suit the occasion.

While there is herein shown a single embodiment of my invention for the purpose of clear disclosure, it will be manifest that changes may be made in the configuration and distribution of parts within the scope 90 of the appended claims.

Having described my invention, what I claim as new and desire to secure by Letters Patent is:

1. A foot support in the nature of an insole for shoes, consisting of a body layer 100 of material having a pocket formed in its under surface adjacent to one end and otherwise normally flat throughout, said body

- layer having a lengthwise slit in one edge terminating short of both ends thereof, a pad in said pocket, a pocket-closing layer of material attached to the lower surface of said body layer, and a thin flat resilient re-enforcing strip disposed in said slit and in uniform contact throughout its length with the portions of the body strip above and below its slit.
- 10 2. A foot support in the nature of an insole for shoes, consisting of a body layer of material having a pocket formed in its under surface adjacent to one end and otherwise normally flat throughout, said body layer having a lengthwise slit in one edge

terminating short of both ends thereof, a pad in said pocket, a pocket-closing layer of material attached to the lower surface of said body layer, and a thin flat resilient re-enforcing strip disposed in said slit and in uniform contact throughout its length with the portions of the body strip above and below its slit, the said re-enforcing strip being of substantially less width than the said slit whereby to permit the slit portions of the body layer to close against one another. 20

In testimony whereof I have hereunto subscribed my name.

WILLIAM M. SCHOLL.
